(57) **CLAIM**

(**) Term: **14 Years**

The ornamental design for a cartridge for a dry powder inhaler, as shown and described.

(21) Appl. No.: **29/319,776**

DESCRIPTION

(22) Filed: **Jun. 13, 2008**

FIG. 1 is a side and top perspective view of our new cartridge design in a containment configuration..

(51) **LOC (9) Cl.** **29-02**

FIG. 2 is a side and top perspective view of the cartridge in a dosing configuration.

(52) **U.S. Cl.** **D24/110**

FIG. 3 is a side view of the cartridge as shown in FIG. 1.

(58) **Field of Classification Search** **D24/110,**

FIG. 4 is a back view of the cartridge as shown in FIG. 1.

D24/110.5; 128/203.14, 203.15, 203.19,

FIG. 5 is a front view of the cartridge as shown in FIG. 2.

128/203.21, 203.28, 200.12, 200.14, 205.21;

FIG. 6 is a top view of the cartridge as shown in FIG. 1; and,

424/46

FIG. 7 is a bottom view of the cartridge of FIG. 1.

See application file for complete search history.
